US00D631670S

(12) **United States Design Patent**
Jackson

(10) **Patent No.:** **US D631,670 S**
(45) **Date of Patent:** **** Feb. 1, 2011**

(54) **INSULATION MATERIAL**

(75) Inventor: **Roger Jackson**, St. Helens (GB)

(73) Assignee: **Knauf Insulation Limited**, St. Helens (GB)

(**) Term: **14 Years**

(21) Appl. No.: **29/311,136**

(22) Filed: **Dec. 31, 2008**

(51) **LOC (9) Cl.** **05-06**

(52) **U.S. Cl.** **D5/99**

(58) **Field of Classification Search** **D5/20, D5/43, 44, 47, 53, 62, 99; 428/67, 141, 322.2, 428/411.1, 143, 144; D25/149, 151; D9/531; 52/127.1, 404.3, 461**

See application file for complete search history.
